J. W. COAST, JR.
ART OF CRACKING HYDROCARBONS.
APPLICATION FILED SEPT. 27, 1917.

1,400,800.

Patented Dec. 20, 1921.

UNITED STATES PATENT OFFICE.

JOHN W. COAST, JR., OF TULSA, OKLAHOMA, ASSIGNOR TO THE PROCESS COMPANY, OF TULSA, OKLAHOMA, A CORPORATION OF MARYLAND.

ART OF CRACKING HYDROCARBONS.

1,400,800.

Specification of Letters Patent. Patented Dec. 20, 1921.

Application filed September 27, 1917. Serial No. 193,473.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Cracking Hydrocarbons, of which the following is a full, clear, and exact description, reference being had to the accompanying 10 drawing, forming a part of this specification.

This invention relates to improvements in the art of cracking and otherwise treating hydrocarbons, the object being to avoid the 15 losses which have heretofore been incurred by evaporation during the operations of refining cracked hydrocarbon products.

In following the ordinary practice, the vapor passing from a cracking still is condensed under a high pressure, or under a 20 pressure of at least one atmosphere. High pressure in the condenser has been considered desirable for the reason that under a relatively low pressure, the lightest fractions 25 in the vapor will pass away in the form of gas. These volatile fractions are most valuable constituents of the cracked product, but it is quite difficult to retain them in a liquid state. So the condenser of the ordinary 30 cracking apparatus is usually maintained under a very high pressure for the purpose of liquefying these light fractions. In this connection, it is highly important to observe that the object is to eventually utilize 35 the light hydrocarbons in a liquid state. If condensation under pressure does not result in the preservation of the very volatile fractions for commercial use in a liquid state, it fails to accomplish the desired result. Al- 40 though the use of high pressure in the condenser is strongly advocated by experts in this art, and realizing that such pressure is now used in most successful and highly developed cracking apparatus, I believe that 45 condensation under high pressure and the subsequent treatment of the product results in a loss, instead of a gain, of the volatile fractions. For the following reasons, I prefer to crack the hydrocarbons under a high 50 pressure, and to condense the cracked product in a vacuum.

To subject the hydrocarbons to a high temperature while in a liquid state, it is, of course, desirable to maintain the contents of 55 the still under a high pressure, and if this pressure is maintained in the condenser a

large volume of highly desirable volatile fractions will pass from the apparatus in a liquid condition. However, it must be understood that the cracked product passing 60 from the condenser is not in condition for commercial use. Before being placed upon the market as gasoline, or the like, it is agitated and mixed with acid, redistilled, or otherwise treated in such a manner that the 65 most volatile fractions pass away freely in the form of gas, carrying with them a large volume of less volatile but very valuable fractions which would otherwise remain in the liquid. In other words condensation 70 under pressure results in the temporary recovery of very volatile hydrocarbons which would otherwise pass from the condenser in the form of gas, but when the product is undergoing subsequent treatment, these light 75 fractions escape into the atmosphere and carry away other very valuable portions of the liquid. As a consequence, the actual yield of gasoline is greatly reduced by the loss of the lightest fractions which escape 80 during the treatment of the cracked product, and also by the loss of heavier hydrocarbons which pass away with the lighter fractions.

To avoid all of these losses, I crack the hydrocarbons under pressure in any suitable manner, so as to produce a vapor containing the relatively low boiling point fractions, but instead of condensing the vapor under a high pressure, I preferably maintain a vacuum in the condenser, thereby preventing the most volatile fractions 90 from passing out in a liquid state. The product, therefore, includes a liquid that can be treated for commercial purposes without incurring the losses that have heretofore resulted from the evaporation of a large volume of the volatile fractions. The light 95 fractions, passing from the condenser in the form of gas, are liquefied in any suitable manner, and blended with a heavier hydrocarbon liquid to produce a commercially valuable hydrocarbon mixture. These light 100 fractions may be returned to, and blended with, the cracked distillate after the latter has been subjected to the refining operations.

Figure I is a diagrammatical view of an apparatus adapted for use in following the new method.

Fig. II is an enlarged vertical section of the absorption chamber.

To illustrate the invention I have shown

a cylindrical cracking still 1 arranged above a heating chamber 2 and connected, by means of an air cooled vapor pipe 3, to a reflux condenser 4. 5 designates a vapor pipe leading from the reflux condenser to a main condensing coil 6, from which the cracked distillate is conducted through a pipe 7 and into a receiving tank 8.

The cracking apparatus is particularly 10 adapted for use in cracking high boiling point products of distillation such, for example, as the distillates or residues resulting from the distillation of crude petroleum. The oil to be treated is introduced into the 15 cracking still in any suitable manner, and any desired pressure may be obtained by regulating a valve 9, preferably located in the vapor pipe 5. The pressure in the still, vapor pipe 3, and reflux condenser 4, is 20 preferably greater than 50 pounds per square inch, for example, about 80 pounds per square inch, and the temperature of the contents of the still preferably ranges from about 600° F. to about 800° F. If the pressure regulating valve 9 is arranged in the 25 vapor line as herein shown, the contents of the still can be maintained under the desired high pressure, and a vacuum may be maintained in the condenser 6. The hydro- 30 carbons are preferably cracked under pressure and condensed in a vacuum. The term "vacuum" as herein used is intended to cover any pressure lower than the normal atmospheric pressure, and does not necessarily 35 mean an absolute or perfect vacuum.

10 designates a gas conductor leading from the condensate pipe 7 to a vacuum pump 12, and 13 is a gas conductor leading from the receiving tank 8 to the vacuum 40 pump. The conductors 10 and 13 are provided with valves 14 and 15 respectively. When the apparatus is in operation, one or both of the valves 14 and 15 are open, and the vacuum pump 12 is actuated to maintain 45 a vacuum in the condenser 6 and receiving tank 8. The cracked distillate is thus subjected to a vacuum, and as a result, a large volume of the lightest and most volatile fractions pass through the gas conductors 10 and 13, to the vacuum pump 12. It 50 is to be understood that the invention is not limited to the production of a vacuum in the precise manner herein shown, the main object being to collect the lightest and most volatile fractions from the cracked distillate, before the latter is subjected to the refining operations.

The gas passing from the vacuum pump, 60 under pressure, as will be hereinafter described. The cracked distillate discharged into the receiving tank 8, may be refined in any suitable manner. To illustrate a suitable refining apparatus, I have shown a tank

16, wherein the distillate may be agitated 65 and treated with acid as is well understood in the art, and a steam still 17 for distilling the hydrocarbons passing from the tank 16. The cracked distillate passing from the tank 8, flows through a pipe 18 to a pump 19 70 whereby it is forced into the tank 16. After undergoing the agitation and acid treatment in the tank 16, the distillate is discharged through a pipe 20 to a pump 21 which forces it into a steam still 17. The vapor passing 75 from the steam still, flows through a pipe 26 to a condenser 27, and the refined distillate is discharged through a pipe 28 to a tank 29.

Prior to this invention, the vapor passing 80 from cracking stills has been condensed under pressure, and the condensate has, therefore, included a large percentage of very light volatile fractions, which cannot be easily retained in a liquid state. In the following ordinary practice such condensate, 85 including the very light fractions, is usually agitated, distilled, and otherwise handled in such a manner that very large volumes of the most volatile fractions escape in the form of gas, carrying with them a large 90 volume of less volatile but very valuable fractions which would otherwise remain in the liquid. In following the new method, all of these losses are avoided.

The refined oil passes from the tank 29, 95 through a pipe 30 to a pump 31, and thence through a pipe 32 to an absorption tank 33. The gas, passing from the vacuum pump 12 is conducted through a pipe 34 to a gas compressor 35, whereby it is compressed and forced through a water cooled coil 36, and thence through a pipe 37 leading into the absorption tank 33. The lower end of pipe 37 is provided with a perforated discharge member 38 located near the bottom of the absorption tank 33. Some of the compressed 100 gas is liquefied in the cooling coil 36 and the remaining gaseous fractions are discharged through the perforated member 38 in the absorption tank. The refined oil is pumped from the tank 29 to the absorption tank 33, as previously pointed out, and a body of this oil is maintained in the absorption tank. 39 designates a gas conductor leading from the top of the absorption tank, 105 and 40 designates a conductor through which the liquid is discharged from the absorption tank to a storage tank 41. Valves 42 and 43, in the conductors 39 and 40, are adjusted to maintain the contents of the absorption tank under a pressure of, preferably about 110 150 pounds per square inch. The compressed gas bubbling up from the discharge member 38, commingles with the refined distillate while the contents of the absorption tank are maintained under pressure, and under these conditions a very large percentage 115 of the light hydrocarbon fractions in the gas will be readily absorbed by the refined dis- 120

125

tillate. The permanent gas, or unabsorbed gas, passes out through the conductor 39, and the refined distillate blended with very light volatile fractions, pass out through the 5 conductor 40 and into the storage tank 41. This tank contains the light fractions, taken from the cracked distillate, and restored in the absorption tank after the distillate has passed through the refining apparatus.

10 I claim:—

In the art of making gasolene, the method which comprises cracking and distilling hydrocarbons, subjecting the resultant distil-

late to a vacuum so as to withdraw the lightest and most volatile fractions in the form of 15 gas, thereafter refining the distillate, and subsequently returning said gas to the refined distillate by commingling the gas with said distillate and maintaining the mixture under pressure so as to blend the refined hydrocarbons with the lighter and more volatile fractions. 20

In testimony that I claim the foregoing I hereunto affix my signature.

JOHN W. COAST, JR.
